UNITED STATES PATENT OFFICE.

HENRY BERNHARD HILGER, OF FORT WAYNE, INDIANA.

PHONOGRAPH-DISK-RECORD CABINET.

1,274,712.

Specification of Letters Patent. Patented Aug. 6, 1918.

Application filed May 21, 1917. Serial No. 170,009.

To all whom it may concern:

Be it known that I, HENRY B. HILGER, a citizen of the United States, residing at Fort Wayne, in the county of Allen and

5 State of Indiana, have invented certain new and useful Improvements in Phonograph-Disk-Record Cabinets; and I do declare the following to be a full, clear, and exact description of the invention, such as will enable others skilled in the art to which it ap-

10 pertains to make and use the same.

This invention relates to an improved cabinet construction for phonograph disk records and other similar articles.

15 One object of the invention is to provide a cabinet of this character, the component parts of which are arranged in extremely compact form in order that the cabinet may have a maximum holding capacity within

20 a minimum space.

A further object of the invention is to provide an efficient means for withdrawing or ejecting the records from the cabinet.

An additional object of the invention is 25 to provide a novel manner of pivotally mounting the record holders.

A still further object is to generally improve upon devices of this class by the provision of an extremely simple, strong, durable and inexpensive construction, and one 30 which will be efficient and reliable in operation and well adapted to the purpose for which it is designed.

With these and numerous other objects 35 in view, the invention resides in certain novel features of construction, and the combination and arrangement of parts as will be hereinafter fully described and claimed.

In the accompanying drawings forming 40 a part of the application and in which similar reference characters designate like parts throughout the several views:—

Figure 1 is a front elevation of a cabinet constructed in accordance with this invention;

45 Fig. 2 is a horizontal sectional view of the cabinet taken on the plane indicated by the line 2—2 of Fig. 1;

Fig. 3 is a vertical sectional view of the 50 cabinet, the record holding levers being shown in full lines in their overbalanced position, and one of them being shown in its depressed position in dotted lines;

Fig. 4 is an enlarged detail sectional view 55 taken on the plane indicated by the line 4—4 of Fig. 3; and

Fig. 5 is a detail side elevation of a portion of the lower end of one of the slats or partitions.

Referring more particularly to the drawings, the reference numeral 1 designates the cabinet proper which is divided into a plurality of vertically disposed compartments 2 by means of partitions, the latter extending vertically from the top to the bottom of 60 the cabinet. In the present instance, these partitions are shown in the form of pairs of aligned slats 3 constructed from comparatively thin stock.

These slats 3 are spaced apart at their 70 upper and lower ends by means of strips 3^a, through which and the slats 3 extend rods or bolts 3^b having nuts 3^c threaded on one of their ends. By this construction it will be seen that the record holder proper may be 75 manufactured independently of the cabinet proper, and quickly and easily applied thereto by placing the various parts of the record holder in proper position in the cabinet and passing the rods 3^b through the 80 walls of the latter and the openings in the slats 3 and strips 3^a.

The opposing sides of the forwardmost slats 3 are provided with recesses 4, which partake of the nature of V-shaped grooves 85 extending from the forward edges of the slats and inclining downwardly and rearwardly.

Disposed between the slats 3 are individual record holder levers 5 having apertures 6 extending horizontally therethrough at a point adjacent their forward ends. Disposed in these apertures 6 are balls 7, the latter being slightly greater in diameter than the thickness of the levers 5, whereby 90 the opposite sides of the balls project beyond the sides of said levers, and these sides are disposed in the grooves 4, thereby forming pivots for said levers. Thus, it may be seen that the levers 5 are overbalanced and 95 incline toward their rear ends.

The reference numeral 8 designates a horizontally disposed frame which is mounted at the forward part or front of the cabinet and disposed slightly above the 105 forwardmost ends of the levers 5. Slidably mounted in the frame 8 is a plurality of keys 9, the lower free ends of the shank portions of which engage the forwardmost ends of the levers as clearly shown by Fig. 110 3 of the drawings.

In using the device, the disk records to be

stored away are placed in the cabinets 2, their lower edges resting upon the levers 5. When it is desired to withdraw any particular record from the cabinet for use or otherwise, the respective key 9 is depressed. This causes the forward end of the lever 5 which supports this particular record to also be depressed and the rear end raised, thus placing said lever in a forwardly inclined position instead of a rearwardly inclined position. This obviously causes the record to roll forwardly and have its forward edge project a sufficient distance beyond the partitions to allow it to be removed. Upon releasing the pressure of the key 9 the weight of the overbalanced end of the lever will cause it to drop and restore the key to its normal position.

The device is of very compact construction by reason of the slats and levers being made of thin material. Should it be desirable to remove any of the levers 5, this can be readily done by sliding them forwardly, as when this is done the balls 7 are withdrawn from the grooves 4.

From the foregoing description, taken in connection with the accompanying drawings, the construction, use and operation of the invention will be readily understood without a more extended explanation.

As various changes in form, proportion, and in the minor details of construction may be resorted to without departing from the spirit of this invention, it is to be understood that I do not wish to be limited to the precise construction herein shown and described.

Copies of this patent may be obtained for five cents each, by addressing the "Commissioner of Patents, Washington, D. C."

I claim:—

1. In a cabinet construction for phonograph disk records, the combination of a plurality of vertically disposed partitions to receive records therebetween, having registering recesses in their opposing sides, levers disposed between said partitions for supporting the records and having apertures therein, and balls disposed within said apertures and projecting beyond the sides of said levers, said balls being received in the recesses in the opposing sides of said partitions to form pivotal mountings for said levers.

2. In a cabinet construction for phonograph disk records, the combination of a plurality of vertically disposed partitions to receive records therebetween having registering V-shaped grooves in their opposing sides, said grooves extending from the forward edges of said partitions and inclining rearwardly, levers disposed between said partitions for supporting the records and having apertures therein, and balls disposed in said apertures and projecting beyond the sides of said levers, said balls being received in the grooves in the opposing sides of said partitions to form pivotal mountings for said levers.

In testimony whereof I have hereunto set my hand in the presence of two subscribing witnesses.

HENRY BERNHARD HILGER.
